UNITED STATES PATENT OFFICE

148,462

DESIGN FOR A CHILD'S CHAIR

Homer C. Debo, Los Angeles, Calif.

Application October 14, 1946, Serial No. 133,931

Term of patent 14 years

(Cl. D15—1)

To all whom it may concern:

Be it known that I, Homer C. Debo, a citizen of the United States, residing at Los Angeles, in the county of Los Angeles and State of California, have invented a new, original, and ornamental Design for a Child's Chair, of which the following is a specification, reference being had to the accompanying drawing, forming a part thereof.

Fig. 1 is a side view of a child's chair showing my new design;

Fig. 2 is a rear view;

Fig. 3 is a front view; and

Fig. 4 is a top view thereof.

I claim;

The ornamental design for a child's chair, as shown.

HOMER C. DEBO.
